UNITED STATES PATENT OFFICE.

JAMES P. HANSON, OF OSHKOSH, WISCONSIN.

LOG-JACKING MECHANISM FOR SAW-MILLS.

SPECIFICATION forming part of Letters Patent No. 293,245, dated February 12, 1884.

Application filed December 8, 1883. (No model.)

To all whom it may concern:

Be it known that I, JAMES P. HANSON, a citizen of the United States, residing at Oshkosh, in the county of Winnebago and State of Wisconsin, have invented certain new and useful Improvements in Log-Jacking Machines for Saw-Mills; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to improvements in a log-jacking machine for that class of saw-mills in which the logs are drawn up an inclined logway alongside of the log-carriage by an endless revolving chain, known as a "bull-chain," or other equivalent device preparatory to being sawed.

The object of my invention is to provide a device for automatically stopping the log as it is being drawn into the mill at the desired point alongside of the carriage, and which will, as soon as said log is removed from the endless chain, cause said chain to commence its rotary movement again.

The construction of my invention is explained by reference to the accompanying drawings, in which Figure 1 represents a side elevation, Fig. 2 represents a ground plan, and Fig. 3 represents a detail.

Like parts are represented by the same reference-letters throughout the several views.

A represents the log as it is being drawn into the mill by and upon the endless chain B preparatory to being sawed. Motion is communicated to said chain B from the operative power of the mill through band C, pulley D, shaft E, friction-pulleys F and G, shaft H, gears I and J, shaft K, and sprocket-gear L. One end of the shaft E is provided with a movable journal-box, M, which permits the shaft E and the friction-pulley F to be moved slightly toward and from the shaft H, whereby the peripheries of the friction-pulleys F and G are brought together and separated. When the endless chain B is relieved of the weight of the log, the peripheries of said friction-pulleys F and G are brought in contact, and thus retained by the gravity of the weight U acting through

rope V, pulley C, lever S, link W, and movable journal-box M, whereby said endless chain is set in motion and the logs placed thereon are drawn into the mill. As the logs are thus drawn to the desired position upon the endless chain to be rolled upon the carriage the front end of the log is brought in contact with the buffer T, whereby said buffer is thrown back, together with the sliding bar R. The rearward motion of the buffer T and bar R is communicated to the friction-pulley F, as hereinafter explained. The block T is supported upon the standards h h, which are pivoted upon the rod I'. The end toward the left of bar R and brace K' are pivoted to the upper end of the standards h h. The end of rod R toward the right is loosely fitted in a recess formed in the top of the post O', upon which post it is supported and guided.

J' J' are stops, which are rigidly attached to the bar R, and limit the leftward movement of said bar by contact with the side of the post O'. The office of bar R is to both carry bar L' and to move the buffer T back and hold it in position after the log has been removed from the endless chain B, which backward motion is caused by the gravity of weight N acting through rope O, which rope passes around pulley P and Q, and is attached to bar L'.

H' is a brake, which is brought in contact with the periphery of the friction-wheel G, and thus arrests its movement as soon as the friction-pulley F is thrown out of contact therewith. The lower end of the brake H' is pivoted to bar w, and is inclined away from the friction-pulley G at such an angle that it is kept from contact with said pulley by its own gravity. The upper end of the brake H' is provided on its respective sides with bars of strap-iron, I", which extend upward on the respective sides of the bars R and L'.

Y is a pin, which extends through and projects from the respective sides of bar L', and is adapted to engage against the strap-irons I" as said bar L' moves toward the right, thereby forcing the brake H' back against the friction-pulley G, and thus arrests the motion of said pulley as soon as it is relieved from contact with the pulley F. The arrangement of said friction-pulleys is such that a slight motion only of the lever S is required to engage or disengage

their peripheries. To the upper end of the lever S is also attached a rope, B', which passes to the right, and is carried over the pulley D', and from thence toward the left 5 alongside of the logway at a convenient height to be reached by the operator, whereby, if desired, he may, by drawing downward upon said rope, disengage the friction-pulleys and stop the log before it reaches the buffer 10 T. The bar L' is retained upon the bar R by the plates a a, which plates are rigidly bolted to the respective sides of said bar L' at its ends, passing down on the respective sides of bar R, their lower ends being connected together beneath the bar R by girds b b in such a manner as to permit said bar L' to slide freely upon said bar R. The upper left-hand end of bar L' is provided with brackets E' and F', through the upper end of which brackets passes a loosely-fitting rod, M''. The rod 15 M'' is provided at its right-hand end with a screw and nut, by which the relative position of said bars R and L' may be changed to each other by turning said nut toward the right or left on said screw.

My invention operates as follows: As the log A is drawn into the mill upon the endless chain B, it is brought in contact with the buffer T, moving the same back, together with 20 bars R and L', whereby the arm T' is brought in contact with the lever S and the friction-pulleys F and G are thrown out of contact. Simultaneously with said backward movement the pin Y is brought in contact with the strap-irons I'', which are rigidly attached to the upper end of brake H', thereby forcing said 25 brake against the friction-pulley G, thus stopping the backward motion of the bar L'. If, however, the momentum of the log carries it 30 still farther toward the right, the bar R will be moved independently of the bar L', said movement being resisted by the gravity of the weight N until the log and bull-chain are brought to rest. As soon as the log is removed from 35 the endless chain B, the weight N forces bar R, buffer T, and rod M'' back, when the nut on rod M'' strikes against the bracket F', which is rigidly attached to bar L', whereby said 40 bar L' is carried back with said nut, first relieving brake H' from contact with the friction-pulley T and permitting the lever S to 45 be drawn toward the left by the gravity of the weight U, whereby the friction-pulleys F and G are brought in contact, and the endless 50 chain is started and continues to revolve until the succeeding log is drawn into the mill and brought in contact with the buffer, as 55 previously mentioned.

The advantages of my invention are obvious, 60 as I not only dispense with one person in the mill for stopping and starting the endless chain, but the log is also stopped with greater precision at the right time and place, and the endless chain is always started as soon as the log 65 is removed and notice communicated to the

person below that another log is wanted, and no delay is caused in waiting for logs, as is frequently the case when the starting of the chain is dependent upon the attention of a person.

Having thus described my invention, what I claim as new, and desire to secure by Letters Patent, is—

1. In a log-jacking machine, the combination of a buffer against which the approaching log is adapted to be brought in contact, a stationary friction-pulley or equivalent from which motion is communicated by gears and shafts to the bull-chain, a movable friction-pulley or equivalent communicating with the operative power of the mill, and means for communicating motion from said buffer to said movable pulley, whereby said pulleys are separated by contact of the approaching log with said buffer and the bull-chain and log 80 thereon automatically stopped at the desired point, substantially as set forth.

2. In a log-jacking machine, the combination of a stationary friction-pulley and means for communicating motion therefrom to the 90 bull-chain, a movable pulley communicating through bars and levers with a movable buffer, against which the approaching log is adapted to be brought in contact and moved in one direction, and weights suspended from ropes 95 adapted through their connecting medium to bring said friction-pulleys in contact and move said buffer when relieved from the log in the opposite direction, thereby starting the bull-chain, substantially as and for the purpose 100 specified.

3. In a log-jacking machine, the combination of standards h h, buffer T, bar R, rod M'', bar L', said bar L' adapted to move on bar R, retaining-plates a a, cord O, as attached to 105 bar L, and adapted to operate pulley Q in bar R, and pass beneath bar R, over pulley B, in post O', said rope being provided at its lower end with weight N, lever S, provided with rope V, from the end of which is suspended a weight, U, said bar L' being provided with brackets E' and F', for the reception of rod M'', arm T', adapted to be brought in contact with lever S, pin Y, adapted to communicate motion to the brake H', brake H', 110 adapted to check the motion of the friction-pulley G, link W, movable journal-box M, shaft E, band-pulley D, friction-pulleys F and G, shaft H, gears I and J, shaft K, sprocket-gear L, and bull-chain B, said shafts, pulleys, 115 and gears being adapted to communicate motion from said friction-pulley G to the endless chain, all substantially as and for the purpose 120 specified.

In testimony whereof I affix my signature in 125 presence of two witnesses.

J. P. HANSON.
